CLAIM

The ornamental design for a flexible edge molding, as shown and described.

DESCRIPTION

FIG. 1 is a perspective view of a flexible edge molding showing my new design, this being shown slightly bent so as to follow a curved line;

FIG. 2 is an end view of the flexible edge molding of FIG. 1;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a second embodiment of a flexible edge molding, the front, top, rear, and bottom being plain and unornamented.
